UNITED STATES PATENT OFFICE

CARL ARNOLD, OF NUERMBERG, GERMANY

MECHANICAL TOY

Application filed August 25, 1931, Serial No. 559,226, and in Germany March 26, 1931.

This invention relates to a toy in which inside a hoop or the like rigidly fixed on a base plate, a vehicle, for example a motor car is moved in a circle. With this object in view 5 a spring actuated propelling device and also a clockwork built into the vehicle cooperate in such a manner, that the vehicle must travel in a circle along the path determined by the hoop in a certain time owing to the centrifugal force. During the circulating movement 10 of the vehicle, spark beams are also produced.

An embodiment of the invention is illustrated by way of example in the accompanying drawing in which:

15 Fig. 1 shows the toy in side elevation, partly in section.

Fig. 2 is a bottom plan view of the propelling device.

20 Fig. 3 shows the vehicle on a larger scale in bottom plan view.

Brackets 2 and 3 mounted on a base plate 1 carry rigidly a hoop 5, provided with running grooves and slot 4. A vehicle 7 provided with a clockwork 6 is placed in the running grooves of the hoop 5. A spring tensioning or propelling device is mounted under the base plate 1 and designed to propel the vehicle 7 so that it travels in a circle in the hoop 5. This device consists of a rod 8 with a collar 9 and with an upwardly projecting nose 10 on its front end, its rear end being bent to form a circle. This nose 10 projects through a slot 11 into the hoop 5 and bears against the vehicle. A spiral spring is arranged on the rod 8 between the collar 9 and the base plate 1 designed to hold the rod under tension. The releasing of the rod 8 is effected by turning a lever 14, provided with a nose 13 at one end and bent outwardly at an angle at the other end. A spiral spring 15 fixed to the nose 13 of the lever 14, holds this lever in pressing position, when the spring is tensioned.

The toy operates in the following manner: 45 In order to impart a circulating movement to the vehicle 7, the rod 8 is pulled back, so that the spring 12 is compressed. The clockwork of the vehicle is then wound and the vehicle placed in the running grooves of the hoop. By pressing inwards the lever 14

on the outer side of the base plate 1, the portion of the lever within the base plate is pressed outwards at its end and consequently disengages from the spring controlled rod 8 so that this rod or its nose 10 can rapidly move forward in the slot 4 of the loop 5 and in the slot 11 of the base plate 1. The vehicle 7, against which the nose 10 of the rod 8 strikes, is propelled in the hoop 5 with great force. At the same time as the releasing of the tensioning or propelling device, the clockwork 6 built in the vehicle 7 is released and the vehicle continues to travel in a circle in the hoop until this clockwork has run down. In order to prevent the vehicle from dropping out of the hoop, as its speed decreases, a spring controlled gripper nose 16 is provided under the vehicle and pressed outwards by the expanding clockwork spring until it comes to bear under the loop slot 4. The vehicle is then prevented from travelling in its running direction and rolls back in the hoop. After winding the clockwork, so that the gripper nose 16 recedes, and the propelling device is tensioned, the operations can be repeated.

In order, when the vehicle is travelling in the hoop, to produce spark beams the hoop 5 has a friction surface 17 of suitable material, extending over the inner circumference of the hoop. On the rear end of the vehicle an oscillatable cerium stone lever 18 is arranged, which slides on the friction surface for the purpose of producing sparks.

I claim:

1. A mechanical toy, comprising in combination a hoop having a slot and travelling grooves, a vehicle loosely placed in the grooves of said hoop, and a spring actuated tensioning and propelling device adapted to operate through said slot and to cause said vehicle to travel in a circle in said hoop owing to the centrifugal force.

2. A mechanical toy as specified in claim 1, comprising in combination with the hoop the tensioning and propelling device and the vehicle placed in said hoop, a clockwork mechanism on said vehicle adapted to be actuated by said device and to drive said vehicle so

that it continues to run in said hoop until said clockwork has run down.

3. A mechanical toy as specified in claim 1, comprising in combination with the hoop 5 having a slot and the vehicle placed in said hoop, a clockwork adapted to drive said vehicle, a spring of said clockwork, a spring controlled gripper nose adapted to be forced by said expanding clockwork spring into the 10 slot in said hoop and to thus stop the vehicle and prevent same from falling out of said hoop.

4. A mechanical toy as specified in claim 1, comprising in combination with the tensioning 15 and propelling device a spring controlled oscillatable two-armed lever adapted to be actuated from the outer side and to release said propelling device.

5. A mechanical toy as specified in claim 1, comprising in combination with the hoop and the vehicle placed therein, a friction band 20 extending over a considerable length of the inner circumference of said hoop, a lever oscillatably mounted on said vehicle, and a cerium stone on said lever adapted during the 25 circulating movement of said vehicle to rub against said band and produce beams of spark behind said travelling vehicle.

In testimony whereof I affix my signature.
CARL ARNOLD.
